AUTOMATIC RAILWAY SWITCH

Filed July 22, 1925

2 Sheets-Sheet 2

UNITED STATES PATENT OFFICE.

ALVA S. NORMENT, OF RICHMOND, VIRGINIA.

AUTOMATIC RAILWAY SWITCH.

Application filed July 22, 1925. Serial No. 45,323.

To all whom it may concern:

Be it known that I, ALVA S. NORMENT, a citizen of the United States, and a resident of the city of Richmond, in the county of 5 Henrico and State of Virginia, have invented a new and useful Improvement in Automatic Railway Switches, of which the following is a full, clear, and exact description.

10 My invention relates to railway switch operating mechanism and more particularly to the automatic type of switches controlled by the operator of the car without the necessity of alighting therefrom.

15 A further object is to provide a means for throwing the switch while the car is in motion thereby eliminating any delay caused by the operator of the car having to stop, alight, and throw the switch by hand, and 20 also to provide a means for throwing the switch without the use of electricity thereby conserving the great amount of electricity necessary to throw an electric switch.

25 A still further object is to provide a simple and inexpensive device constructed to operate the switch by a plunger at the front end of the car which is pressed down causing a shoe to be pushed into a groove in the street surface and coming in contact 30 with an underground bar which in turn actuates a jointed rod attached to the switch point. This device will permit the successful operation of the switch in congested traffic for the reason that the switch is operated only when the car reaches the underground mechanism and therefore cannot be 35 operated by any car preceding or following.

With the foregoing and other objects in view, the invention consists of the features 40 of construction and arrangement of parts hereinafter fully described and claimed, it being understood that the drawings are for illustrative purposes only and that various modifications may well be made without departing from the spirit of the invention as 45 set forth by the claims.

In the drawing forming a part of this application and in which like-designating characters refer to the corresponding parts throughout the several views,

Figure 1, is a top plan view of the track and switch mechanism at a switch point, with parts of cover shown broken away;

50 Figure 2, is a vertical and longitudinal cross section, taken on lines 2-2 of Figure

1, and also showing a cross sectional view of one of the car attachments;

55 Figure 3, is a vertical and longitudinal cross section, taken on lines 3-3 of Figure 1;

60 Figures 4 and 5, are detailed vertical transverse sectional views, on an enlarged scale, taken respectively on lines 4-4 and 5-5 of Figure 1;

65 Figure 6, is a similar view, taken on line 6-6 of Figure 2, and disclosing more particularly the relation of the switch throwing means to the track proper.

70 Referring more in detail to the drawings, number 1 designates the main rails, suitably embedded in concrete 2. The siding is shown at 3 with the switch-point 4, to which is attached the switch throwing mechanism.

75 The greater portion of this mechanism is placed in a pit 5 which has a cover 6 designed to exclude foreign matter, such as ice, snow or dirt, and to prevent damage from the street traffic. The longitudinal section of pit 5 is lined on the surface edges with

80 guard rails 7 forming grooves 8 in which the shoes of the car attachment are pushed in the operation of the switch mechanism. The underground attachment comprises a base 9 for pivotally mounting, as at 10 the bar 11 and saddle 12. This bar 11 is placed

85 in and attached to the pivoted saddle 12 with set screws 13 in a manner to permit of its being readily removed and replaced. The saddle 12 has for its purpose the carrying

90 of the bar 11 and permit of its being pivotally moved. The saddle 12 should be attached to the bar 11 at the proper distance to insure throwing the switch-point 4 the full width of the rail.

95 The actuating bar 11 is constructed with a T-shaped end to permit the rollers 14 being attached at each side of this end, designed to project through slots 15 into the grooves 8 and contact with the shoe of the car attachment. This bar 11 is braced and

100 supported by guides 16 which also form the underground framework. The other end of the bar 11 is constructed to form ears 17 permitting the bar 11 to be pivotally attached at 18 to block 19 which is carried by

105 the jointed rod 20. This jointed rod 20 is pivoted at 21 to rod 22 which in turn is pivotally fastened at 23 to the switch-point 4. The rods 20 and 22 are constructed to

110 pivot at 21 and 23 to permit the switch-

110

point-connected rod 22 to rock with the switch-point. This rocking is usually caused when a car passes over a switch-point which has become worn. The joints at 21 5 and 23 eliminate all possibility of strain or breakage caused by any motion of the switch-point 4.

The block 19 is held in place on one side by two sliding sleeves 24 carrying a spiral 10 spring 26 and constructed to form collars 25 at the extreme ends which support the spiral spring 26 and which are adjusted in place by two locknuts 27. On the other side of the block 19 there is another spiral spring 15 28 which operates to the reverse of spiral spring 26 and is held in place and adjusted by two locknuts 29. The purpose of the spiral springs 26 and 28 is to provide a cushioning action to permit the switch- 20 point to be thrown from one side to the other without striking the sides with force, and causing possible damage to the structure. At this point it may be well to state that if there should happen to be any foreign 25 matter such as stones or ice on the rail which would prevent the action of the switch-point, the operation of the switch throwing mechanism would only result in contracting the spiral springs and leaving the 30 switch-point idle, thereby preventing any possible damage to the mechanism. The spiral springs 26 and 28 also permit taking up any wear which may occur to the underground bar 11 by tightening the locknuts 27 35 or 29. It is recommended that the spiral springs be constructed with sufficient strength to throw the switch-point while still permitting the springs to be compressed for the emergency above described. The 40 jointed rods 20 and 22 with attachments are affixed within a lateral pit 30 which has a cover 31 to exclude foreign matter such as snow, ice or dirt, and also to prevent damage from surface traffic.

The switch throwing mechanism further comprises two car attachments which are affixed in parallel positions under the car flooring 32 at a distance apart to correspond with the grooves 8 of the underground attachment, and are each designed to throw the switch-point one way or the other. The two car attachments are identical in design and construction and it is therefore understood that only one will be described. Each car attachment comprises a housing 33 which is bolted to the flooring at 34 and through which passes the plunger 35 carrying the shoe 37. This housing is braced 36 and reinforced. At the lower end of the plunger 35 there is affixed a shoe 37 which may be detachably secured to permit of its being replaced when worn. The operator of the car depresses the plunger 35 with his foot causing the shoe 37 to be pushed into the groove 8 and coming into contact with the

roller 14 carried by the underground bar 11. When released, the plunger 35 is brought back to its original position by two contractile springs 38 which are attached respectively to the shoe 37 and the braces 36.

At a point midway between the rollers 14 and the ends of the grooves 8, there are placed in the grooves 8 two sloping plates 39, attached at parallel points, which elevate the plunger 35 and drop it again, thereby warning the operator that the shoe 37 has passed the roller 14 and that the plunger 35 should be released. A set of inclined plates 40 are also attached at the ends of the grooves 8 to elevate the shoes 37 to the street level if the operator has failed to notice the signal given by the sloping plates 39 and has not released the plunger 35.

Having shown and described the construction and operation of this switch operating mechanism, what I now claim as my invention is:—

1. A switch operating mechanism comprising a jointed rod attached to the switch point, a bar which is attached to a pivotally mounted saddle, being connected at one end to the jointed rod and at the other end carrying rollers which extend through slots into grooves formed by the underground framework, a set of two plungers, each carrying a shoe at its terminal, which is pushed into the groove when the plunger is depressed, and which contacts with the roller carried by the underground bar.

2. A switch operating mechanism comprising a jointed rod pivotally attached to the switch-point to permit any rocking motion of the switch-point, said rod carrying spiral springs on both sides of a connecting block which provide a cushioning action in throwing the switch-point, a bar attached to the connecting block and carried in a saddle pivotally attached to the base of the underground framework, said bar also carrying rollers on its T-shaped end which protrude through slots into the grooves, a set of two plungers, each having affixed at the lower end a shoe which is pushed into the groove when the plunger is depressed, and which contacts with the roller carried by the underground bar.

3. A switch operating mechanism comprising a jointed rod attached to the switch-point, pivotally constructed to permit any rocking motion of the switch-point without causing damage to the structure, said rod carrying a connecting block held in place by spiral springs which provide a cushioning action in throwing the switch-point and providing a means to permit the underground bar to be actuated when the switch point is forcibly made to remain idle because of foreign matter on the rail, this being accomplished by the contracting of the spiral springs, a bar attached to the connecting

block and carried in a saddle pivotally attached to the base of the underground framework and designed to pivot with the saddle, said bar also carrying rollers at its T-shaped 5 end which protrude through slots into the grooves, a set of two plungers, each operating through a housing properly braced and securely fastened under the car flooring, and having two contractile springs to return said 10 plungers when depressed to their original position, each of said plungers also having affixed at the lower end, a shoe which is

pushed into the groove when the plunger is depressed, and which contacts with the roller carried by the underground bar, a set of 15 sloping and inclined plates attached in the grooves, designed respectively to warn the operator that the shoe has passed the roller, and to elevate the shoe to the surface level, if the operator has failed to observe the signal of the sloping plates. 20

In testimony whereof I affix my signature hereto.

ALVA S. NORMENT.
